UNITED STATES PATENT OFFICE.

DANIEL H. MILLER, OF COUNCIL BLUFFS, IOWA.

VETERINARIAN'S OBSTETRICAL INSTRUMENT.

1,130,098.

Specification of Letters Patent. Patented Mar. 2, 1915.

Application filed December 27, 1913. Serial No. 809,119.

To all whom it may concern:

Be it known that I, DANIEL H. MILLER, a citizen of the United States, residing at 11 South First street, Council Bluffs, in Pottawattamie county, Iowa, have invented a new and useful Improvement in Veterinarians' Obstetrical Instruments, of which the following is the specification.

My invention relates to improvements in an instrument used by veterinarians in obstetrics in which an interlocking series of rods or links connect the hooks or attaching members to a suitable handle for manipulation.

The objects of my improvement are: first, to provide such an obstetrical instrument that can be readily separated and taken apart and packed in an instrument case; second, to provide such an instrument, combining flexibility with provisions for turning the attached part by a manipulation of the handle and of moving the whole by pushing or pulling the same without disconnecting the parts. I attained these objects by the structure illustrated in the accompanying drawings in which—

Figure 1 is an elevation of the whole device; Fig. 2 is an elevation showing the flexibility of the joint; Fig. 3 is a similar elevation showing the formation of the joints upon the several parts and showing the means of disconnecting same; Figs. 4 and 5 are elevations showing the joints of the various parts; Fig. 6 is a side elevation of the handle part; Fig. 7 is an elevation showing the engaging hook; Fig. 8 is an elevation of another form of the engaging hook. Fig. 9 is an end elevation of a double engaging hook shown in Fig. 8, and Fig. 10 is a cross section of the same hook.

Similar letters refer to similar parts throughout the several views.

This instrument consists of a handle, *a*, and the necessary engaging hook, *b*, or plurality of hooks, *d*, together with any number of links, as *c* and *c'* adapted to engage the handle, *a*, and the engaging hook, *b* in such manner that the instrument will be flexible between the hook, *b* and handle *a* and is capable of being thrust forward or pulled backward without disconnecting.

The disconnecting of the parts of the instrument are accomplished by so forming links with the handle, *a*, that the joints are slightly opened so that brought in an extreme position with the openings of the joints toward each other they will slip into each other, then by turning them slightly they become engaged so as to be flexible but are able to be twisted or pulled back or pushed forward.

The instrument is used in the ordinary manner by taking hold of the engaging hook, *b*, or *d*, and engaging it in the fetus to be removed, the handle *a* being operated by the other hand to turn the engaging hook *b*, or *d*, as is necessary and to thrust the whole instrument forward or draw it backward as the case may be. Besides the ordinary hook, *b*, the instrument can be supplied with the double hook *d*. This consists of two hinged hooks *x* and *y* pointing toward each other. When held in the hand the finger can draw back the link, and open the hook over the fetus to be engaged and then closed upon it without lacerating the surrounding tissues, the link, *c*, may then be pushed upon the sides of the hooks which are notched or corrugated to hold the link *c*.

What I claim is:—

1. In an obstetrical instrument, an engaging hook, a manipulating handle and one or more links, the engaging hook, handle and links having disengaging and interchangeable joints.

2. In an obstetrical instrument, a manipulating handle, one or more links and one or more engaging hooks, said handle, links and engaging hooks having disengaging and interchangeable joints formed thereon.

3. In an obstetrical instrument, a manipulating handle, one or more links and engaging hooks and a means for locking the engaging hooks into the fetus; the said handle, links and engaging hooks having disengaging and interchangeable joints formed thereon.

DANIEL H. MILLER.
